Attorney

UNITED STATES PATENT OFFICE.

EDWARD M. LOFTUS, OF ST. PAUL, MINNESOTA.

PLIERS.

1,418,312.

Specification of Letters Patent. Patented June 6, 1922.

Application filed January 3, 1921. Serial No. 434,490.

To all whom it may concern:

Be it known that I, EDWARD M. LOFTUS, a citizen of the United States, residing at St. Paul, in the county of Ramsey and State of Minnesota, have invented a new and useful Pliers, of which the following is a specification.

My invention relates to combination tools, and the object is to provide an improved 10 combined pliers and wrench.

In the accompanying drawing, Figure 1 is a side view of a pair of pliers provided with means for readily converting it into a wrench or preventing its spreading when 15 used as pliers;

Fig. 2 is Fig. 1 in closed position;

Fig. 3 is a right-hand edge view of Fig. 2;

Fig. 4 is a portion of Fig. 3 showing a modification;

20 Fig. 5 is Fig. 4 further modified;

Fig. 6 is a section on line 6—6 in Fig. 1; and

Fig. 7 is a detail view of the locking cam of the device in a modified form.

25 Referring to the drawing by reference numerals, 8 and 9 designate the two levers or members of the pliers pivoted together by a bolt 10 which is movable in a transverse slot 11 in one of the members so as to make 30 the gap 12 between the jaws 8^a and 9^a changeable as to size for grasping extra large or extra small nuts, gas pipes or other articles.

The jaw 8^a is provided at one side with an embossment 13 forming an angular tooth 35 14. Said tooth is arranged and adapted to engage in a serrated segmental face 15 of a cam 16 which is pivoted at 17 to the lever 9 at a point almost opposite from the gap 12 relative to the pivot 10. The pivot 17 40 is provided with a spring washer 18 for holding the cam in any position to which it may be swung by the operator.

In Figs. 1, 2, 3 and 6 the head 10^a of the pivot bolt 10 is shown countersunk flush with the member 9 so that the straight or plane cam 16 may swing over it. In Fig. 4 is shown that the head 10^b of the bolt may project and the cam 16 may have an offset 19 to make it clear the head. But as this requires the boss 13 to be extra high 50 I have shown in Fig. 5 that the extra height may be obviated by giving the cam a second offset 20. With either of these improvements I am able to swing the cam to the idle position shown in Fig. 1, stopping against a lug 21 and being out of the way for using the pliers only, and when a nut, as 22 in Fig. 1, is to be turned the tool is converted into a wrench by swinging the cam 16 as 16^x or similar position into engagement with the tooth 14 at such point of the segmental face as will correspond to the size of the nut 22 operated on.

What I claim is,—

1. The combination with a pair of pliers comprising two crossing jaw levers with a main pivot through the crossing, one of said levers having near the jaw a lateral projection forming a tooth, a spring-held cam pivoted to the other jaw rearward of the main pivot and having a serrated cam face adapted to engage the tooth on the jaw of the first-mentioned lever.

2. The structure specified in claim 1, and a lug on the lever carrying the cam for positively stopping the cam in its idle position.

3. The structure specified in claim 1, said pivot at the crossing of the levers having a head projecting beyond the adjacent lever, and said cam having a clearing to allow it to swing over said head.

In testimony whereof I affix my signature.

EDWARD M. LOFTUS.
